AIR CONDITIONING SYSTEM UTILIZING
REFRIGERATIONRobert T. Palmer, Sharon, Mass., assignor to B.
F. Sturtevant Company, Inc., Boston, Mass.

Application March 13, 1936, Serial No. 68,657

15 Claims. (Cl. 62—6)

This invention relates to air conditioning systems using refrigeration and relates more particularly to methods and apparatus for conserving refrigeration and fan power in such systems.

5 In some types of buildings such for example as stores and restaurants where the load varies considerably during different portions of a period, it has been proposed to provide air cooling coils through which a refrigerant is circulated and to 10 control the volume of air passing over the coils in accordance with the number of people in the space within which the conditioned air is supplied.

According to this invention, the air volume, 15 and the refrigerating energy is varied in accordance with the number of people in the space supplied with conditioned air. In one embodiment of the invention, a plurality of cooling coils extend, in the conditioner, cross-wise the air stream, and the number of the active coils is varied in accordance with load conditions. The inactive coils are 20 shunted out of the air flow to reduce the resistance of the air through the conditioner, and the air volume is reduced.

In one embodiment of the invention, the controls of the air conditioning system are adjusted 25 in accordance with the number of persons in the enclosure as determined by an actual count.

An object of the invention is to condition air at minimum expense.

30 Another object of the invention is to efficiently save fan power and refrigerating energy in an air conditioning system, when the load is reduced.

Another object of the invention is to adjust the controls of an air conditioning system supplying 35 air to an enclosure, in accordance with the number of persons in the enclosure as determined by actual count.

Other objects of the invention will be apparent 40 from the following description taken together with the drawings.

The invention will now be described with reference to the drawings, of which:

Fig. 1 is a diagrammatic view of one embodiment of the invention utilizing several groups of cooling coils in the conditioner; each group of coils being served by a separate source of refrigeration;

Fig. 2 is a diagrammatic view of another embodiment of the invention in which all groups of air cooling coils are supplied by a single source of refrigeration; and

Fig. 3 is a diagrammatic view of another embodiment of the invention in which controls are 55 varied by a device which counts the actual num-

ber of persons in the space served with conditioned air.

With reference to Fig. 1, there is illustrated what is known as a by-pass system of the general type shown by the Patent No. 1,670,656 to W. L. Fleisher. In the present case, the conditioner 5 has mounted therein, cross-wise the air stream, the three groups of evaporator coils, 6, 7 and 8. The coils 6 are supplied through the expansion valve 9 with any suitable refrigerant from compressor #1 and condenser #1. The coils 7 are likewise supplied from compressor #2 and condenser #2, through valve 10, and the coils 8 are supplied through valve 11 from compressor #3 and condenser #3. In front of, with respect to air flow, of the coils 6, are the shutters 12 adjusted to open or closed position by the motor 13. Similar shutters 14 adjusted by motor 15 are before the coils 7, and similar shutters 16 adjusted by motor 17 are before the coils 8.

The thermostat 18 is mounted in the path of the mixed recirculated and outside air leaving the mixing chamber 19. The recirculated air from the enclosure 20 enters the mixing chamber 19 through the duct 21, and the outside air after passing through the filter 22, enters the mixing chamber 19 through the duct 23.

The control thermostat 18 is seen to be responsive to the condition of the air to be conditioned. In the past, it has been customary to place such control thermostats in the space being conditioned or in the recirculated air duct, on the theory that the load offered by the outdoor air is constant while the load within the space fluctuates to a great extent. In many cases, however, the load offered by the outside air has been found to fluctuate while the load offered by the recirculated air remains substantially constant so that it is preferred to so mount the control thermostat 18 that it responds to the changes in load of the total air entering the conditioner.

The thermostat 18 upon a decrease in the temperature of the air entering the conditioner 5, indicating that less refrigeration is required, acts first to open the energizing circuit of the shutter control motor 17, causing it to close its associated shutters 16 in front of the coils 8, as shown by the drawings. The suction temperature of the refrigerant entering the compressor #3 through the thermo-responsive valve 24, then falls, causing the thermostatic element within the valve 24 to open the circuit including the motor 25, the solenoid 26, the wires 27, 28 and 29, causing the compressor #3 to shut down.

At the same time, due to the deenergization of

the solenoid 26, its armature 30 falls to open a circuit including the fan driving motor 31, the wires 32 and 33, the contact 34, and an electric source disconnecting the motor 31 from across the line leading to the electric source. The armature 30 then closes an electric circuit including the electric source, the contact 35, the armature 36, the contact 37, the resistor 38 and the fan motor 31, thus connecting the fan motor in series with the resistor 38 to the electric source, causing the speed of the fan 39 and the air volume it delivers, to be reduced. The fan then acts to draw a reduced volume of mixed recirculated and outside air through the active coils 7 and 8, the inactive coils 8 offering no resistance to the air flow.

If this reduction of cooling surface and air volume is not sufficient, the thermostat 18 next acts to open the energizing circuit of the shutter control motor 15, causing it to close its associated shutters 16 in front of the coils 7. The temperature of the refrigerant entering the compressor #2 then falls causing the thermo-responsive valve 40 to open a circuit including the compressor driving motor 41, the solenoid 42 and an energizing electric source, causing the compressor #2 to shut down and the solenoid 42 to become deenergized, this latter causing the armature 36 to fall to open the previously described circuit including the contact 37 and resistor 38, and to close a circuit including the contact 43, the resistor 44, the resistor 38 and the fan motor 31. This connects the fan motor 31 in series with both resistors 44 and 38 causing another reduction in fan speed and volume.

When, as in the case of an outdoor temperature drop, the above described reductions in cooling surface and air volumes are insufficient, the thermostat 18 opens the energizing circuit of the shutter control motor 13 causing it to close its associated shutters 12 in front of the coils 6 and to open the shutters 45 in a by-pass through the conditioner 5 around all of the coils. The resulting drop in the temperature of the refrigerant entering the compressor #1 through the thermo-responsive valve 46 causes it to open the energizing circuit of the compressor driving motor 47 to shut down the compressor #1.

The system then operates automatically as a ventilating system until a change in the temperature of the outside or of the recirculated air indicates that refrigeration is required, following which the thermostat will act to place the requisite cooling surface into service and to regulate the fan volume accordingly.

During the operation of the system as described in the foregoing, by-pass air enters through the duct 48, the mixing chamber 49 at the output side of the conditioner 5, and serves to raise the sensible heat of the air leaving the conditioner. No damper adjustment of the by-pass air is necessary due to the fact that its volume varies in accordance with the total air volume and the effective coil surface, so that at all times the system is in balance.

The embodiment of the invention illustrated by Fig. 2 is essentially the same as that described above in connection with Fig. 1, except that a single source of refrigeration, which may be an indirect source, supplies refrigeration to all three groups of air cooling coils, and no thermostat such as control thermostat 18 of Fig. 1 is used. The coils themselves determine the amount of cooling surface and air volume required. If when all coils are in service, the refrigerant returned

to the source shows by arriving at too low a temperature, that the maximum cooling effect is not required, first one and then the others of the groups of coils are rendered inactive. Most of the apparatus is similar to that shown by Fig. 1 so that the same reference characters will be applied to apparatus common to both figures.

The refrigeration supply 50 supplies a cooling liquid through the pipe to the coils 6, 7 and 8 which are in series with respect to fluid flow when all are in service. Between coils 6 and 7 is the two way valve 52 which may be adjusted by the solenoid 53 to close off the entrance of the liquid to the coils 7 and to return it through the pipe 54 to the supply 50. Between coils 7 and 8 is a similar valve 55 which may be adjusted by the solenoid 56 to close off the entrance of the fluid to the coils 8 and to return the fluid leaving coils 7 to the supply 50, through the pipe 57. Normally, when all of the coils are active, the refrigerant passes through all coils and returns to the source 50 through pipe 58.

In the common return pipe 59 to the source 50 are mounted the thermostats 60 and 61. With all three groups of coils 6, 7 and 8 active, when the load on the coils is such that their total effect is not necessary, this is indicated by too low a temperature of the refrigerant passing first through the thermostat 60, on its return to the source 50. This causes the thermostat 60 to open a circuit including the electric source, the solenoid 26, the shutter control motor 17 and the solenoid 56, causing the solenoid 56 to adjust the valve 55 to by-pass the refrigerant around the coils 8; causing the motor 17 to close its associated shutters 16, and causing the solenoid 26 to connect the resistance 38 in the circuit of the fan motor 31, as described in connection with Fig. 1, to decrease the fan speed and volume.

If this reduction is not sufficient, the thermostat 61 responds to open a circuit including the electric source, the solenoid 42, the shutter control motor 15, and the solenoid 53. This causes the solenoid 53 to adjust the valve 52 to by-pass the refrigerant around the coils 7; causes the motor 15 to close the shutters 14 before the coils 7, and causes the solenoid 42 to close a circuit to connect resistors 44 and 38 in the circuit of the fan motor 31 as described above in connection with Fig. 1.

If this reduction is not sufficient, the thermostat 62 in the enclosure 20 opens a circuit including the motor 63 of the refrigeration supply, to discontinue the supply of refrigeration to the coils, and including the shutter control motor 13 causing it to close the shutters 12 in front of the coils 6. At the same time, the motor 13 opens the shutters 45 to enable ventilating air to bypass the coils in the conditioner 5. When the temperature within the enclosure 20 rises above the setting of the thermostat 62, it functions to supply refrigeration to the coils 6. If this is not sufficient, the thermostat 60 places the coils 8 in service.

The embodiment of the invention illustrated by Fig. 3 is similar to that described above in connection with Fig. 1 except that no shutters are placed in front of the coils 6; no by-pass in the conditioner around the coils is provided, and a device which determines the number of persons in the enclosure 20, adjusts the volume of outside air in proportion to the number of persons in the enclosure. The remainder of the apparatus and its method of operation are similar to

that illustrated by Fig. 1 so that the same reference characters are used for this apparatus common to Figs. 1 and 3.

In the fresh outside air inlet duct 23 are mounted the dampers 64 adjustable by the solenoid 65 from one third open to wide open positions. The current supply to the solenoid 65 and to the shutter control motors 15 and 17 is controlled by the counting mechanism which will now be described.

As illustrated no occupants are in the enclosure 20 and the system is running at minimum capacity with only the coils 6 and compressor #1 active; with the outside air damper 64 two thirds closed, and the fan 39 operating at one third volume. During this period of minimum load, the thermostat 63 in the recirculated air duct 21, controls the conditioner 5 by starting and stopping the compressor #1.

Persons entering the enclosure 20 pass in the entrance 66 in single file and in so doing interrupt the light beam from the light source 67 to the photo-electric cell 68. The current impulses in the cell 68 are amplified by the amplifier 69 and are then fed into the counter 70 which may be similar to those disclosed by Patent Re. 18,567, issued August 9, 1932 to R. J. Wensley et al., and which as the impulses accumulate, rotate the gear 71, in mesh with the gear 72, which is threaded internally to mesh with the threads on the shaft 73 so that the shaft 73 on which is mounted the resistor 74 moves from left to right (facing the drawing) as the number of people entering the enclosure 20 increases. During the movement of the shaft 73 and resistor 74, the contact 75 moves across the face of the resistor 74 to decrease the resistance of and increase the current flow in, the energizing circuit of the armature coil 76 of the galvanometer indicated generally by 77.

During this time, any persons leaving the enclosure 20, pass in single file through the exit 78 and in so doing, interrupt the light beam between the source 79 and the photo-electric cell 80, causing current impulses to be amplified in the amplifier 81 and to flow into the counter 82, similar to the counter 70, but rotating in the opposite direction to tend through the action of the gears 83 and 84 to move the shaft 73 and resistor 74 to the left (facing the drawing), thus tending to increase the resistance in the energizing circuit of the galvanometer coil 76. When a person enters and another person leaves the enclosure at the same time, the counters 70 and 82 oppose each other and the resistor does not move. As more persons enter than leave the enclosure 20, the resistance in the energizing circuit of the galvanometer coil 76 is decreased to cause the coil 76 and its contact arm 85 to move to the right (facing the drawing) in proportion to the decrease in resistance, which in turn is proportional at any time, to the number of persons who have entered the enclosure 20 and have not left.

As the number of persons in the enclosure 20 increases, the coil 76 moves the arm 85 to the right (facing the drawing), and the contact 86 is moved across the resistance 87 to decrease the value of the resistance in the energizing circuit of the solenoid 65, causing it to move its damper 64 towards open position, proportional to the number of persons in the enclosure.

When the persons in the enclosure 20 have increased to a predetermined number, the arm 85 moves against the contact segment 88 closing the energizing circuit of the shutter control motor

15, causing it to become energized to adjust the shutters 14, before the coils 7 to open position. The thermostat 40 then causes the compressor #2 to start up.

When the persons in the enclosure have further increased to a larger predetermined number, the contact arm 85 moves against the contact segment 89 to close the energizing circuit of the shutter control motor 17 causing it to adjust its shutters 16, before the coils 8, to open position. The thermostat 24 then places the compressor #3 into operation.

The thermostat 63 in the recirculated air duct 21 acts to prevent too cold air from being supplied into the enclosure 20 by shutting down the compressor #1 when the recirculated air indicates that too much cooling is being done in the conditioner. This has the double effect of decreasing the refrigeration effect, and of increasing the by-pass air effect due to the relatively high temperature untreated air passing through the now inactive coils 6 to mix with and raise the sensible heat of the air passing in contact with the active coils.

The speed and volume of the fan 39 is automatically increased by the action of the relays 26 and 42, when the coils 7 and 8 are placed in service, so as to vary the total volume of air passing through the conditioner in accordance with the load within the enclosure 20. The volume of fresh air is varied by the adjustment of the fan 39 when the total volume handled by the fan is adjusted, but the proportion of fresh air to recirculated air is adjusted by the damper 64 which also, of course, varies the total volume of fresh air entering the conditioner.

A volume of exhaust air equal at all times to that of the outside make-up air admitted into the conditioner, is vented from the enclosure through outlets which may be special exhaust outlets or which may be the ever present cracks and crevices.

While the means for the control of volume of the fan has been illustrated as a speed control means, it is obvious that the volume may be regulated by adjustment of spin inducing vanes in the fan inlet. For example, fans provided with control vanes such as are disclosed by the Patents No. 1,846,863, or No. 1,989,413 to H. F. Hagen may be had with automatic adjusting mechanism such as disclosed in application Ser. No. 81,455 filed May 23, 1936.

Whereas several embodiments of the invention have been described for the purpose of illustration, it should be understood that the invention is not to be limited to the exact arrangement described, as many departures may be made by those skilled in the art, after having had access to this disclosure.

What is claimed is:

1. Air conditioning apparatus comprising a plurality of air coolers, means for supplying refrigerant to said coolers, a fan for passing a stream of air through said coolers and into a room to be supplied with conditioned air, and means responsive to a function of the psychrometric condition of the air in said room for varying the volume of air moved by said fan and the number of said coolers exposed to said air stream.

2. Air conditioning apparatus comprising a plurality of air coolers, means for supplying refrigerant to said coolers, a fan for passing a stream of air through said coolers and into a room to be supplied with conditioned air, and

means responsive to a function of the psychrometric condition of the air in said room for varying the volume of air moved by said fan, the number of said coolers supplied with refrigerant, and the number of said coolers exposed to said air stream.

3. Air conditioning apparatus comprising an air cooling chamber, a plurality of groups of air cooling coils in said chamber, a fan for passing a stream of air through said chamber and for discharging it into a room to be supplied with conditioned air, means for selectively supplying said groups of coils with refrigerant, and means responsive to the temperature of one of said groups of coils for varying the number of said groups of coils to be supplied with refrigerant.

4. Air conditioning apparatus comprising a plurality of air coolers, a fan for passing a stream of air through said coolers and for discharging it into a room to be supplied with conditioned air, means for selectively supplying said coolers with refrigerant, and means responsive to the temperature of the refrigerant returned to said last mentioned means for varying the number of said coolers to be supplied with refrigerant.

5. Air conditioning apparatus comprising an air cooling chamber, a plurality of groups of air cooling coils in said chamber, a fan for passing a stream of air through said chamber and for discharging it into a room to be supplied with conditioned air, means for selectively supplying said groups of coils with refrigerant, and means responsive to the temperature of the refrigerant returned to said last mentioned means for varying the number of said groups of coils to be supplied with refrigerant.

6. Air conditioning apparatus comprising a plurality of coolers, a fan for passing a stream of air through said coolers and for discharging it into a room to be supplied with conditioned air, means for selectively supplying said coolers with refrigerant, means responsive to the temperature of the refrigerant returned to said last mentioned means for varying the number of said coolers to be supplied with refrigerant, and for removing the ineffective coolers from said air stream.

7. Air conditioning apparatus comprising in combination a room to be supplied with conditioned air, an air cooling chamber, air cooling means in said chamber, a fan for moving air through said chamber and for discharging it into said room, means for supplying refrigerant to said air cooling means, means for determining the approximate number of people in said room, and means including said last mentioned means for controlling the conditioning of the air by said apparatus.

8. Air conditioning apparatus comprising in combination a room to be supplied with conditioned air, an air cooling chamber, air cooling means in said chamber, means for supplying outside air into said chamber for conditioning, a fan for moving air through said chamber and for discharging it into said room, means for supplying refrigerant to said air cooling means, means for determining the approximate number of people in said room, and means including said last mentioned means for varying the volume of outside air entering said chamber.

9. Air conditioning apparatus comprising in combination a room to be supplied with conditioned air, an air cooling chamber, air cooling means in said chamber, means for supplying outside air into said chamber for conditioning,

a fan for moving air through said chamber and for discharging it into said room, means for supplying refrigerant to said air cooling means, means for determining the approximate number of people in said room, and means including said last mentioned means for varying the volume of outside air entering said chamber, and the supply of refrigerant to said air cooling means.

10. Air conditioning apparatus comprising in combination a room to be supplied with conditioned air, an air cooling chamber, air cooling means in said chamber, means for supplying outside air into said chamber for conditioning, a fan for moving air through said chamber and for discharging it into said room, means for supplying refrigerant to said air cooling means, means for determining the approximate number of people in said room, and means including said last mentioned means for varying the volume of outside air entering said chamber, the supply of refrigerant to said air cooling means, and the total volume of air supplied by said fan into said room.

11. Air conditioning apparatus comprising in combination a room to be supplied with conditioned air, a plurality of air coolers, means for supplying outside air to said coolers for conditioning, a fan for moving air through said coolers and for discharging it into said room, means for supplying refrigerant to said coolers, means for determining the approximate number of people in said room, and means including said last mentioned means for varying the volume of outside air entering said chamber, and the number of said coolers in contact with said air stream.

12. Air conditioning apparatus comprising in combination a room to be supplied with conditioned air, an air cooling chamber, a plurality of groups of air cooling coils in said chamber, means for supplying outside air into said chamber for conditioning, a fan for moving air through said chamber and for discharging it into said room, means for supplying refrigerant to said air cooling means, means for determining the approximate number of people in said room, and means including said last mentioned means for varying the volume of outside air entering said chamber, the number of said groups of coils in contact with the air stream through said chamber, and for controlling the supply of refrigerant to said coils.

13. Air conditioning apparatus comprising in combination, an enclosure to be supplied with conditioned air, a conditioning unit, means for supplying conditioned air from said unit into said enclosure, means for supplying fresh air into said unit, counting means for determining the approximate number of occupants of said enclosure, said last mentioned means including totalizing means for adding increases and for subtracting decreases in the approximate number of occupants, and means utilizing said totalizing means for varying the volume of fresh air in accordance with the number of occupants of said enclosure.

14. Air conditioning apparatus comprising in combination, an enclosure to be supplied with conditioned air, a conditioning unit, means for supplying conditioned air from said unit into said enclosure, means for supplying fresh air into said unit, means for supplying air recirculated from said enclosure into said unit, counting means for determining the approximate number of occupants of said enclosure, said last

mentioned means including totalizing means for adding increases and for subtracting decreases in the approximate number of occupants, and means utilizing said totalizing means for varying volumes of fresh and recirculated air substantially in accordance with changes in the number of occupants of said enclosure.

15. Air conditioning apparatus comprising in combination, an enclosure to be supplied with conditioned air, a conditioning unit, means for supplying air recirculated from said enclosure into said unit for conditioning, means for supplying fresh air into said unit, means for sup-

plying air recirculated from said enclosure as bypass air, to the output side of said unit, counting means for determining the approximate number of occupants of said enclosure, said last mentioned means including totalizing means for adding increases and for subtracting decreases in the approximate number of occupants, and means utilizing said totalizing means for varying the volumes of fresh air, recirculated air, and bypass air as changes in the number of occupants 10 of said enclosure take place.

ROBERT T. PALMER.
